Primary Examiner—Robert M Spear

Assistant Examiner—Karen Acker

(57) **CLAIM**

The ornamental design for a carton, as shown and described.

DESCRIPTION

FIG. 1 is a perspective view of a carton illustrating our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed lines shown in the drawings are for illustrative purposes only and form no part of the claimed design.

The broken lines in the drawings represent unclaimed environmental subject matter.
